UNITED STATES PATENT OFFICE.

WILLIAM E. GASTON, OF TORRINGTON, CONNECTICUT.

BOTTLE-CLOSURE.

1,168,386.

Specification of Letters Patent. Patented Jan. 18, 1916.

Application filed December 3, 1914. Serial No. 875,213.

To all whom it may concern:

Be it known that I, WILLIAM E. GASTON, a citizen of the United States, residing in Torrington, in the county of Litchfield and State of Connecticut, have invented certain new and useful Improvements in Bottle-Closures of which the following is a specification.

This invention relates more particularly to that class of bottle-closures which is especially designed for use in bottling mineral waters, beer and other liquids requiring the bottles to be sealed against leakage of either liquids or gases under considerable pressure, and to hold the contents with a high degree of security.

My present invention pertains to the general form of bottle closure described in my allowed and co-pending application, Serial No. 737,779, filed Dec. 20, 1912, and also in my co-pending application, Serial No. 66,238, filed Dec. 11, 1915.

A principal object of the present improvements is to furnish a closure of that class in which a minimum amount of packing material will be required, and which may be so arranged and combined as to secure a high degree of uniformity in operation under varying conditions, with a reduction of cost and a minimum proportion of defective closures.

Other objects and advantages are pointed out and more fully explained in the following description.

In the drawings accompanying and forming a part of this specification, Figure 1 is a side elevation of a bottle closure made in accordance with my present improvements. Fig. 2 is a central vertical sectional view showing the several parts assembled in position ready for the setting operation.

Fig. 3 is a sectional view similar to the right-hand portion of Fig. 2, but greatly enlarged, for more clearly illustrating certain features of the closure. Fig. 4 is a vertical sectional view similar to Fig. 3, and showing an intermediate state of the setting operation. Fig. 5 is a similar vertical central sectional view, showing the closure completed, at the end of the setting operation. Fig. 6 is a view similar to Fig. 5, and is a diagram for illustrating certain features of the packing member in its rela-

tions to the other parts of the closure. Fig. 7 is a diagram illustrative of the lines of force between certain points and members in the completed closure, for more fully explaining the mode of operation thereof. Fig. 8 is a view similar to Fig. 3, for showing certain features of my present invention in a modified construction.

For convenience of comparison, Figs. 3, 4 and 5 are all drawn in similar relation to the meridian line X , X , which coincides with the axis of the closure.

Similar characters designate like parts in all of the views.

It will be remembered that when a moldable but resilient and resistant packing-disk is laid over the bottle-mouth and then simply pressed into place in the usual manner by a locked-on metal cap, the substance of the disk is subject to compression over a wide annular zone which therefore has a relatively low intensity of pressure. The effect of that practice has been to so widely distribute the total pressure or sealing-force that the desired high security or sealing-effect was not satisfactorily obtained. These objections are overcome by the improvements set forth in my aforesaid prior application, by means of certain combinations in which there are two concentric bearing-zones, and by other features operating in conjunction therewith, as more fully explained in said application, to which reference may be had. In my present invention,—as in my said prior invention,—the bottle closure operates in accordance with the principle of augmenting the sealing effect by reducing the area and thereby increasing the intensity of the high-pressure contact; and, also, by dividing this high-pressure area into a plurality of relatively non-contiguous, narrow and concentric bearing-zones, so that the principal part of the total stress or pressure exerted upon the bottle face is concentrated upon a relatively small area and is therefore of a relatively greater intensity and consequent higher sealing-effect, than would otherwise be the case.

The application of my improved closure to bottles of the style of formation herein illustrated, may be made by means of instrumentalities which are already well

known, and therefore I have not deemed it necessary to herein illustrate or particularly describe the same.

In the drawings, my improved closure is shown applied to a well known form of bottle-top, B, having a top-face, as C, of the usual form, and also having the lock-face, or lock-rim, k. The cap is designated in a general way by M, and is herein shown provided with a depending outer flange N which surrounds the crown disk and is preferably furnished at its lower edge with some suitable retaining means,—as for instance, the lock-rim-engaging hooks at r,—for enclosing under the lock-face or rim k, when the cap M is in its fully set position, as in Figs. 1 and 5. In practice, however, the lower edge of the flange N may, if preferred, be simply spun under the face k, in a well-known manner; this permits the use of a plainly formed or unserrated lower edge for the flange N. In some cases,—as herein illustrated,—the flange N may have the well known indented formation, whereby the locking-on of the cap is effected in a well-known manner by closing in the lower edge of the flange N to a smaller diameter during the pressing down of the cap, by means of suitable mechanical appliances. This locked-on position is indicated in Figs. 1 and 5, in which the indents or hooks r, are shown engaging directly under the rim or face k. Between the bottle face C and the cap M, a packing member D (see Figs. 2, 3) is located for coacting with those other members in a peculiar manner, which I will now, by the aid of the sectional-views and diagrams, more fully describe.

The packing-face C, (Fig. 3) may be considered as comprising a medial or top-zone d, (Fig. 4) located between the outer, annular bearing-zone b² and the inner, annular bearing-zone b³; in Figs. 4, 5 and 6, these two bearing-zones are distinguished by shaded portions. The zone b² inclines downwardly and outwardly, while the zone b³ is shown with little if any inclination inwardly from said medial zone d. Said outer zone, b², is also shown located on the outer side of the bottle-face, C, so that the fully applied packing member D, may be said to have a wedging action downwardly upon the annular bearing surface b² (see Fig. 5).

The cap and packing member being first assembled on the bottle top as in Figs. 2 and 3, and pressure being then suitably applied over the crown or top of the cap and to the flange N thereof, the said closure members are gradually forced downward and reshaped from their initial positions in Fig. 3, to the successive positions illustrated, respectively, in Figs. 4 and 5. During this progressive operation, the compression applied to the upper edge-zone z² of the mem-

ber D, begins the formation of a pressure-ring or zone n³, in and of the substance of this member and directly above the bearing zone b³, as indicated in Fig. 4, and afterward an outer pressure-ring, n², Fig. 5, but of less depth, is similarly formed.

The cap M when provided with the rim-gripping flange N, has this flange of a depth sufficient for engaging under the bottle-rim at k, and for then extending upwardly and over the relatively thin packing-zone z¹, of the packing-member D, and there forming the sectionally curved flange-grip at g, while the crown disk or top m of the cap (Fig. 3) is adapted to be drawn down or reformed by the setting-pressure into an elevated annular bearing-disk m¹ (Fig. 5), and thus impart to the inner annular sealing-seat b³, an amount of pressure corresponding to that required for so re-forming said cap.

The crown-disk m of the cap M is shown in Figs. 2 and 3, of a preferred form in which the zone m of the disk closely approximates a plane, while in Fig. 5 the outer portion or zone m¹ of this disk is shown drawn downwardly to a line or angle coinciding with the upper surface of the completed pressure-rings or zones n² and n³ of and in the packing member D. This construction provides a considerable initial space at S, Fig. 3, which space is progressively reduced in the succeeded stages of the setting-operation, as indicated at S¹, in Figs. 4 and 5. Thus the initial provision of a crown or top-disk zone at m¹ adapted to be re-formed substantially as set forth during and by the setting operation, provides for beginning the formation of the pressure-ring n³ well in advance of the formation of the pressure ring n², as indicated in Fig. 4.

The packing member D will usually and preferably comprise a plurality of parts arranged and adapted, respectively, for several distinct uses and modes of operation, and whether of integral or composite formation, may be considered as consisting of two zones, layers or disks, as f and h, one applied or formed upon the other. The lower layer h also, preferably, has a composite formation, being provided with the surface member h¹, which I term the sealing-disk or sealing-sheet. The part h¹ should be made of some material or substance suitable for contacting with the contents of the bottle without injury thereto, as for instance, of some sheet-material or resistant layer. In practice I prefer to use for this purpose a relatively separate layer having the required resistant quality and also adapted to serve as a strain-sheet for resisting any excessive deformation of the packing-members f and h.

In the preferred construction illustrated,

the member D may be considered, as to certain features of the combinations, as consisting of a three-layer packing-member comprising a thin, flexible and high-resistance sealing-sheet, h^1 , forming the lower layer and of a diameter covering the three zones, b^2 , d and b^3 of the packing-face C; a second layer, h , consisting of a relatively low-resistance packing-disk of some suitable moldable material applied on said sealing-sheet and preferably having its outer molding-zone, z^1 , of a diameter substantially equal to said sealing-sheet or disk; and a third layer consisting of a forcing-disk, f , 10 preferably of relatively lower resistance, in position on said second layer and of a diameter for only extending over an inner zone, b^3 , which, in practice, may be from one-third to one-half of the total radial width 15 of the three bottle-face zones; but these ratios may be varied. Thus, when arranged substantially as here described, there will be formed in the fully-applied packing-member, two zones of relatively high-pressure, of which one is a relatively thin outer zone or ring and the other is a relatively deep inner zone or ring, and between those two pressure-rings, a zone of low-compression, located over the medial zone d of the 20 packing face, whereby the sealing-action is normally concentrated on the bottle-face upon relatively separated or non-contiguous concentric zones or annular surfaces.

During the formation of the inner pressure ring n^3 , (Fig. 4), and until this formation is well advanced, the upper disk f operates as a forcing member or disk tending to drive downwardly the central portion of the sealing-layers, h , h^1 , while the outer zone, 25 z^1 , of these layers is still free of any substantial compressive force, and is therefore readily conformable to the conditions produced by that forcing action. But later, after said inner ring n^3 is nearly formed, the cap-zone m draws down upon the outer edge of said zone z^1 , and by a sliding and compressive action thereon forces said packing zone or flange against the bearing-line b^2 , and thus draws and forms said zone or 30 flange z^1 outwardly and downwardly, (see Fig. 5).

This peculiar action properly performed, has the effect, in practice, of first seating the packing disk firmly against the inner bearing b^3 , then drawing or wrapping that disk over the medial zone d of the face C, and finally seating the outer edge z^1 firmly against said outer bearing-line b^2 . Thus the 35 said pressure-rings, n^3 and n^2 , are begun in succession but are completed substantially simultaneously. In this operation the disk h is subjected simultaneously to the sealing-pressure and to a diametrical contraction from a larger initial dimension; this tends 40 to produce an inwardly sliding action be-

tween the contacting surfaces of the sealing-disk and the bottle face, and thus tends to draw the sealing sheet, while under an increasing pressure, into a perfect fit or contact over the whole area of the contacting 70 surfaces.

The diameter desirable for the lower disk h , in order that its outer zone z^1 may properly wrap down over the bearing b^3 , will usually be such as to make this disk 75 edge impinge within the flange N of the cap M, when the parts are assembled ready for setting, as illustrated in Fig. 2. This initial excess diameter of the zone z^1 over the inside diameter of the flange N, provides a 80 convenient means for a prior assembling of the caps M and disks D, so the closure may be handled by the bottling operators, and in machines, as a single article, and also may be supplied to the trade in that complete 85 form.

In my present improvements, the moldable forcing-member f has an annular form, it being preferably made from a disk cut out of a suitable material in sheet-form, and the 90 central portion removed, thereby forming a central and relatively large opening into which extends a depressed portion of the cap M, as m^3 , Fig. 3, for positively supporting the annular member f against any considerable amount of diametrical contraction. In the preferred form thereof herein illustrated, the central zone m^3 of the cap is depressed to the extent of forming a resistance wall w , located inside of the said moldable 100 ring, or forcing member f . Thus the depressed zone m^3 is, or may be, integrally connected by the annular wall w with the said cap-zone, m , which is located directly above the inner zone b^3 of the bottle face 105 C. In this arrangement, therefore, the cap-zone m may be said to constitute the annular crown-disk of the closure cap, and to be provided on the outer circumference thereof, with means for engaging the cap-retaining 110 means, as k , of the bottle-top, and also be provided on the inner circumference thereof, with a depending resistance wall, as w , which is surrounded by the annular member 115 f , and supports this member against diametrical contraction.

In Fig. 6 the line 8 illustrates in a diagrammatic manner the general direction in which the cap-stress reacts upon the inner bearing-zone b^3 of the bottle-face, and the 120 series of small divergent arrows at e^2 , indicate how the forces there concentrated, react outwardly against the cap-zone w . The middle portion, n^6 , of said zone n^5 , is shown of a curved or concave form, and located with the concave side thereof toward the said bearing zone b^3 , which thus becomes a center, or focal point therefor. These features, and the mode of applying the cap, 125 operate to bring the packing disk n and the 130

forcing-ring f under compression in such a manner that the substance of said ring f will naturally become adjusted,—during the compressive action,—to an effective bearing as between the bearing-zone b^3 and said cap-zone n^5 , by the occurrence of some sliding or shifting of the ring f , or a part of the substance thereof, within and against said concave cap-zone w . Thus the zone w ,—
 10 when having the form n^5 ,—and as then seen in the sectional views,—may be said to partially surround the point b^3 , and also to constitute a concave pressure-distributing surface located above, and inwardly from, said inner pressure-zone of the bottle-face. The central disk m^3 of the cap when located and arranged as shown in Fig. 6, constitutes one device or form of means for preventing the pressures indicated at e^2 , from deforming the cap-zone n^5 . The cap M , therefore, may be said to comprise a concave pressure-zone n^5 , located in an inclined position, and having an integral connection with the tensioning-zone m^1 lying outside of said pressure-zone b^3 , and also connected with the central or concentric resistance-zone m^3 , which is located in a position, or at a level, considerably below said tensioning-zone. As regards the directions of the forces involved, 25 one of the stress-sections of the zone m^1 , relatively to the zone n^5 , is shown by the arrow r^{14} , while the resistance of inner member m^3 is similarly indicated by the arrow r^{15} .
 In accordance with the features of construction here described, other advantages are 30 illustrated in Fig. 6, where the arrow r^{10} indicates the approximate direction of one of the principal lines of force, or stresses, as between the completely applied cap M , and the bottle-face. On comparing this feature with the other figures as described, it will be evident that the outer flange N being forced under the retaining face k by the usual setting die (not shown) applied in the 35 direction of the arrow r^9 (Fig. 4) operates to draw downwardly the whole cap, as also indicated by the arrow r^{11} , Fig. 6. This operation, however, and after the compression, or downward movement, at r^{11} , has reached 40 the proper point, still draws down the outer portion of the cap-zone m and thereby shifts or flexes this zone from approximately the initial position thereof in Fig. 4, to the final position thereof in Fig. 5, naturally 45 operates to flex,—or turn outwardly,—the said concave wall or zone n^5 , so that this zone may be said to turn or may slightly revolve in an outward direction over and upon the inner compression-zone at n^3 of the pack-50 ing-member or forcing-ring f ; at the same time, the lower part n^6 (Fig. 6) of said zone n^5 is located in a position for operating as a kind of clamp or hook, in the direction of arrow r^{10} , whereby to resist the outward 55 stress upon the cap by a resistance directly

against the inner side of the bottle-face. Thus the strains due to the flange-retaining engagement at k , in any part of the circumference of the closure, are directly and largely balanced and opposed by a resistance 70 in the direction r^{10} and against the bottle-face, at b^3 , in that same part of the circumference, thereby materially reducing the amount of the stress which otherwise would be transmitted across the cap and be there 75 received on the outside of the bottle-face, as herein further illustrated in Fig. 7, and more fully explained in my said prior application.

In the construction above described, the 80 positions of the cap-retaining lock-rim or face k , (see Fig. 6) and also of the inner bearing-zone b^3 , relatively to the said resistance-wall w ,—in the completely applied closure,—is brought down to, or to a point 85 somewhat below, a line, as $y-y$, which passes through said lock-rim and bearing-zone. One advantage of this construction or feature of combination will be evident, since that part of the stress or force which is 90 exerted, on or by one of the faces k , n^5 , in the location and in the direction of said line $y-y$, will be received and resisted by the other said face. Thus the said positioning of the lock-rim k , the inner bearing-zone b^3 , 95 and a zone, as n^5 , of the resistance-wall w , all in a near alinement as here described, naturally provides for such a clamping or clasping action of the cap M upon the bottle-top and packing, as to tend by itself and to 100 a material extent, to hold the closure secured in place.

With relation to the packing-face of the bottle-top and the concentric resistance-wall w , of the crown disk, the packing member 105 may be said to comprise a lower layer or disk as n , having a moldable packing-zone extending to and co-operative with the outer-zone b^2 (Fig. 8) of said packing-face C , and also to comprise an annular upper layer, as 110 f , of an outside diameter less than the outside diameter of said lower disk, n , and having a moldable outer zone, z^2 , superposed upon said lower disk, said upper layer also surrounding and bearing against said resistance-wall. In this construction Fig. 8, the said lower moldable disk, in some instances,—and either with or without the lower or sealing sheet,—may have an annular form, and may then have an inside diameter somewhat larger than the outside diameter of said resistance wall,—as indicated, for instance in Fig. 8. This modification, however, is an improvement not specifically claimed herein, but is reserved 115 to constitute in part the subject-matter of a separate application to be concurrently pending herewith.

The zone or ring, n^3 , of relatively high-pressure as finally completed by and during 120

the setting operation, has normally an outwardly-expansive tendency which actively tends to force such pressure-ring outwardly after the manner of a wedge, between and 5 against the angularly-disposed faces or zones m^1 and b^3 and tends to do this in such a way as to keep a relatively high-pressure on said ring n^3 , when,—as frequently happens in practice,—the cap recedes upwardly 10 by a slight but material amount when the closure is released from the pressure of a cap-setting mechanism. That take-up action of said ring n^3 is especially favored by the location of the said medial zone d , of 15 relatively low-pressure located between and separating the two pressure-zones or rings n^2 and n^3 , so that an actual diametrical enlargement under normal conditions of said inner pressure-ring n^3 does not necessarily or 20 usually require any corresponding enlargement of the outer pressure-ring n^2 , nor involve a material amount of slipping, if any at all, of the said outer ring n^2 upon the bottle face C. And during this operation, 25 any undue diametrical contraction of the packing ring f is prevented by the said annular wall w of the cap M. When thus applied and under the conditions indicated, the said pressure zone n^3 , as will now be evident, 30 acts after the nature of a circular and expandable annular wedge, and this action tends,—as I now apprehend,—to preserve a completely effective sealing pressure on the said inner seal-bearing b^3 of the bottle face, 35 notwithstanding there may be some tendency of the cap to slightly retract upwardly in cases where the closure is maintained for a long period of time, or from other causes.

The operation of the closure members as 40 between each other, gives focal points or bearing points and lines-of-force (triangulation lines) according to a system which is illustrated in Fig. 7, and to which, I now apprehend, the high practical efficiency of 45 the closure may be largely due. From the anchorage 3 (on the face k) in the diagram, Fig. 7, the tension line, or line of force, 4, may be considered as extending directly upwardly to the outer focal point 5, 50 which is located on a line 7, this line being vertical to the outer bearing-zone b^2 ; this bearing line or surface then forms the basis of resistance against the further inward movement, or downward movement, 55 of the said focal point 5. The tension line next turns toward the upper focal point 7, as indicated at 6, the point 7 being on a line, 8, extending downwardly to the inner bearing line or zone b^3 ; from the point 7 60 the tension line, as 9, extends directly across the closure and connects at the point 7' with the similar system of triangulation lines on the opposite side of the closure. Thus the triangulations on opposite sides, 65 respectively, of the closure, when observed

in a sectional view, together constitute a system in which an effective balance of the described opposing forces is obtained.

Having thus described my invention, I claim:

1. In a bottle closure of the class described, the combination with a bottle-top having cap-retaining means for engaging a metal cap, and provided with an upper packing-face comprising a medial top-zone 75 located between concentric inner and outer bearing-zones, and with a metal-cap having an annular crown disk and provided on the outer circumference of said disk with a depending portion in position and arranged for engaging said cap-retaining means of the bottle-top, and also provided on the inner circumference of said disk with a concentrically-located resistance wall depending from the crown disk 80 and of a diameter less than the diameter of said inner bearing-zone, of a packing member comprising a lower packing disk of a diameter greater than the outer diameter of said medial top-zone, and an annular fore- 85 ing member, of a diameter corresponding with the outer diameter of said inner-bearing zone and surrounding said resistance-wall and supported thereby against diametrical contraction, whereby said members 90 are arranged for and form a low-pressure zone which in the fully-compressed packing-member is located directly over the medial-zone of said packing-face of the bottle-top and between concentric zones of relatively high-pressure. 95

2. In a bottle closure of the class described, the combination with a bottle-top having an upper packing-face and cap-retaining means for engaging a metal cap, 105 and having in said upper face three zones comprising a medial top-zone between concentric inner and outer bearing-zones, and with a metal-cap having an annular crown disk and provided on the outer circumference thereof with a depending outer portion in position and arranged for engaging said cap-retaining means of the bottle-top, and provided on the inner circumference thereof with the depending resistance 110 wall of a diameter less than the inside diameter of said packing-face and consisting of a depending cap-zone having a concave packing-seat and located, in the completely applied closure, above and inwardly 115 of the said inner bearing-zone, of a packing member comprising a lower packing disk of a diameter corresponding with the outer diameter of said packing-face, and also comprising an annular moldable fore- 120 ing member of an outside diameter less than that of the outside diameter of said packing-face, and surrounding and diametrically supported against the concave 125 packing-seat of said resistance wall of the 130

cap, said members being arranged for and forming a low-pressure zone which, in the fully compressed packing-member, is located over the medial-zone of the bottle-face and between two concentric high-pressure bearing zones.

3. In a bottle closure of the class described, the combination with a bottle-top having the upper packing face and cap-retaining means for engaging a metal cap, and having in said upper face three zones comprising a medial top-zone between two concentric inner and outer bearing-zones, and with a metal-cap having an annular crown disk and provided on the outer circumference thereof with a depending outer portion in position and arranged for engaging said cap-retaining means of the bottle-top, and provided on the inner circumference thereof with a depending resistance wall of a diameter less than the inside diameter of said packing-face and consisting of a depending cap-zone having a concave packing-seat and located, in the completely applied closure, above and inwardly of the said inner bearing-zone, of a packing member comprising a sealing disk of a relatively large outside diameter and also comprising an annular moldable packing-disk of a relatively small outside diameter and located between said concave packing-seat and the sealing-disk.

4. In a bottle closure of the class described, the combination with a bottle-top having the upper packing-face and cap-retaining means for engaging a metal-cap, and having in said upper face three zones comprising a medial top-zone between concentric inner and outer bearing-zones, and with a metal-cap having an annular crown - disk and provided on the outer circumference thereof with a depending portion in position and arranged for engaging said cap-retaining means of the bottle-top, and provided on the inner circumference thereof with a depending resistance wall which at the lower edge thereof has a diameter less than the inside diameter of said inner bearing-zone, of a packing member comprising a lower packing disk of an outside diameter larger than the diameter of said medial top-zone, and also comprising an annular forcing member of an outside diameter less than the diameter of said outer bearing-zone, said forcing member surrounding and being supported against said resistance wall of the cap, and said members being arranged in position for and forming a low-pressure zone which in the fully-compressed packing-member is located over the medial zone of the bottle-face and between two concentric bearing zones of relatively high-pressure.

5. In a bottle-closure of the class described, the combination with a bottle-top having the upper packing-face and cap-re-

taining means for engaging a metal cap, and with a metal-cap having an annular crown-disk and provided on the outer circumference thereof with a depending portion in position and arranged for engaging said cap-retaining means of the bottle-top, and provided on the inner circumference thereof with a depending resistance wall which at the lower edge thereof has a diameter less than the inside diameter of said packing-face, of a packing-member comprising a lower packing-disk of a diameter corresponding with the outer diameter of said packing-face, and also comprising an annular moldable forcing-member which has an outside diameter less than the outside diameter of said packing-face, and which surrounds and is supported by said resistance wall against diametrical contraction.

6. In a bottle-closure of the class described, the combination with a bottle-top having an upper packing-face and having cap-retaining means for engaging a metal-cap, and with a metal-cap having an annular crown-disk provided on the outer circumference thereof with retaining means in position and arranged for engaging said cap-retaining means of the bottle-top, and provided on the inner circumference thereof with an integral and depending resistance wall, of a packing-member comprising a lower sealing-disk of a diameter corresponding with the outer diameter of said packing face, and also comprising an annular moldable forcing-member which has an outside diameter less than the outside diameter of said sealing-disk, and which surrounds and is supported by said resistance wall against diametrical contraction.

7. The herein-described improvement in caps for bottle-closures, consisting in a metal-cap having an annular crown - disk provided on the outer circumference thereof with a depending outer flange having retaining means, and provided on the inner circumference thereof with a depending and concentrically - located resistance - wall, in combination with a two-part packing member comprising a sealing-disk having an outside diameter corresponding with the inside diameter of said outer flange, and also comprising an annular forcing-disk consisting of a moldable material and located between the sealing-disk and crown-disk and having the inside diameter thereof corresponding to the diameter of said resistance-wall, and having the outside diameter thereof less than the diameter of said sealing-disk.

8. The herein described improvement in caps for bottle - closures, consisting in a metal-cap having an annular crown - disk provided on the outer circumference thereof with bottle-engaging retaining means, and provided on the inner circumference thereof with an annular resistance-wall, in combi-

nation with a packing member comprising a sealing-disk having an outside diameter corresponding with the diameter of said crown-disk, and also comprising an annular 5 forcing-disk consisting of a moldable material and located between the sealing-disk and crown-disk and having the inside diameter thereof corresponding to the diameter of said resistance-wall, and having the outside diameter thereof less than the diameter 10 of said sealing-disk.
